UNITED STATES PATENT OFFICE

2,241,841

SLIDE FASTENER

George M. Beckwith, Meadville, Pa., assignor to
Talon, Inc., a corporation of Pennsylvania

Application October 20, 1938, Serial No. 236,053

6 Claims. (Cl. 2—96)

My invention relates to slide fasteners and certain types of garments in which such fasteners are particularly adapted to be used.

The fundamental object of my invention is to provide an improved slide fastener embodying improved means for allowing adjustment of one side of the slide fastener longitudinally relative to the other side. Heretofore in most instances there has been either a permanent connection of the stringers at one end or a separable connection wherein the parts are permanently set in position at the ends of the stringers allowing for connection only in one relative longitudinal position.

Another object of my invention is to provide an adjustable coupler connection for the stringers of a slide fastener which is in the nature of an accessory which may be made separately and applied to slide fasteners of standard construction.

Still another object is to provide an improved adjustable coupler connection which can be readily moved from one position to another on one fastener stringer when desired and at the same time, which will stay in such desired position even when the other stringer is disconnected from it.

In the accompanying drawing I have shown for purposes of illustration one embodiment which my invention may assume in practice. In the drawing:

Fig. 1 is a plan view of my adjustable coupler and shows it on a conventional type of separating slide fastener assembly;

Fig. 2 is a perspective view of my adjustable coupler removed from the fastener assembly;

Fig. 3 is a longitudinal cross-section on the line 3—3 of Fig. 1;

Fig. 4 is a cross-section on the line 4—4 of Fig. 3;

Fig. 5 is an extended view of a slide fastener assembly equipped with my adjustable coupler showing the fastener in partially closed position;

Fig. 6 shows a garment equipped with a slide fastener incorporating my adjustable coupler for accomplishing adjustment of the waist portion; and

Fig. 7 is a fragmentary view of Fig. 6 showing the waist portion of the garment adjusted to size and the fastener in closed position.

The adjustable stop generally designated 8 has an interior channel 9 extending longitudinally with guiding flanges 10 and 11 respectively, which slidably engage the legs of the fastener elements when the adjustable coupler is in place on the

stringer. In the top surface of the stop is a raised head portion 12 which retains a locking member 13. The locking member 13 is pivoted at 14 on a pin extending through the head and has a locking prong 15 which is urged into locking engagement with the fastener elements by means of a spring 16. The lock may be easily disengaged by pushing down the end opposite the locking finger.

10 As shown in Fig. 1 the adjustable stop is assembled on a conventional type of slide fastener assembly comprising right and left stringers 17 and 18 respectively, carrying on their adjacent edges interdigitating elements 19, and one of the stringers at its lower end carries a suitable stop means 20 which may be formed in any suitable manner or may even comprise a conventional type of separating bottom stop. The opposite stringer carries the conventional type of pin 21 which engages a suitable socket 26 formed in the interior of the adjustable stop adjacent channel 9. The slide fastener assembly carries a conventional type of slider 22.

15 In operation the adjustable coupler may be adjusted at any point along the stringer and locked there by means of the locking arm to adjust one fastener stringer longitudinally relative to the other, and the slider brought adjacent the stop between the guide flanges 23 which flanges may be incorporated to facilitate aligning the slider. The pin member 21 is then fed through the slider and into the socket 26 in a manner practically identical with the operation of the conventional type of separating bottom stop. The 20 slider is then moved in a closing direction and the fastener elements 19 engaged in a manner as best illustrated in Fig. 5.

25 My invention will be particularly applicable to garments where it is desired to have an adjustable waist portion, and will be easily applied. For example, a standard type of fastener may be equipped with my improved adjustable coupler which does not necessitate altering any of the manufacturing procedure or changing any standards. Therefore, when it is desired to use a fastener for an adjusting means, such as on maternity garments, etc., my adjustable coupler 30 may be slid over one of the stringers as heretofore described.

35 As shown in Figs. 6 and 7, a slide fastener equipped with my adjustable coupler is used for the purpose of adjusting the waist portion of a garment. Here one of the stringers of the slide fastener is attached to one portion 24 of the 40 garment about the waist and the complementary 45

50 55 garment about the waist and the complementary

stringer is attached to the underlying portion 25 of the waist. Then to accomplish adjustment of the waist portion it is necessary only to set the adjustable coupler at a desired point, feed the pin through the slider and into the coupler, and then when the slider is closed, the waist portion of the garment will be in proper adjustment as shown in Fig. 7.

While I have shown and described in this application one embodiment which my invention may assume in practice, it will be understood that this embodiment is merely for the purposes of illustration and that various other forms may be devised within the scope of my invention as set forth in the appended claims.

What I claim as my invention is:

1. A slide fastener of the class described comprising a pair of completely separable stringers, means for connecting the end of one stringer to the other stringer comprising a coupling member on the end of one stringer, a cooperating coupling member on the opposite stringer having means to hold said first coupling member, said second coupling member being adjustably mounted on its stringer whereby the two stringers may be connected together in various relative positions.

2. A slide fastener of the class described comprising a pair of completely separable fastener stringers, means for connecting the end of one stringer to the other stringer, comprising a pin member attached adjacent the fastener elements at the end of one fastener stringer, a cooperating coupling member adjustably mounted on the opposite stringer and having means to hold said pin member, said coupling member being adjustably mounted on its stringer whereby the two stringers may be connected together in various relative positions.

3. A slide fastener of the class described comprising a pair of completely separable fastener stringers, means for connecting the end of one stringer to the other stringer comprising a pin member attached adjacent the fastener elements

at the end of one of the stringers, a cooperating coupling member mounted on the opposite stringer, said coupling member having a channel extending longitudinally of its interior for mounting on said stringer, said channel being adapted to hold said pin member, and means for releasably locking said coupling on its stringer for allowing adjustment of one side of the slide fastener longitudinally relative to the other.

4. The combination defined in claim 3 in which said coupling is composed of upper and lower body parts joined together by an integral neck, one of said body parts having a raised head portion enclosing the locking member for adjustably securing said coupling member on the elements on one of said stringers.

5. The combination defined in claim 3 in which said coupling is composed of upper and lower body parts joined together by an integral neck, one of said body parts having a raised head portion enclosing the locking member for adjustably securing said coupling member on one of said stringers, said locking means comprising a locking finger mounted in said head, a prong on said finger adapted to engage the fastener element, a spring automatically urging said finger into locking position, and means for manually releasing said locking prong.

6. In a garment having overlapping body portions, a slide fastener stringer attached to each of said body portions, and capable of being engaged for closing the body portions together in overlapping relation, and means on said slide fastener stringer for connecting the end of one stringer to the other stringer comprising a coupling member on the end of one stringer, and a cooperating coupling member having means to hold said first coupling member, said second coupling member being adjustably mounted on its stringer whereby said overlapping body portions may be connected together in various overlapping relative positions.

GEORGE M. BECKWITH.
